UNITED STATES PATENT OFFICE.

HENRI KAFFERER, OF PARIS, FRANCE, ASSIGNOR TO ASTRA SOCIETE ANONYME, OF BILLANCOURT, SEINE, FRANCE.

AIRSHIP OF THE TORRÈS TYPE.

1,360,646.

Specification of Letters Patent. Patented Nov. 30, 1920.

Application filed March 15, 1918. Serial No. 222,561.

To all whom it may concern:

Be it known that I, HENRI KAFFERER, a citizen of the French Republic, and residing at No. 26 Rue de Clichy, Paris, France, have 5 invented certain new and useful Improvements in Airships of the Torrès Type; of which the following is a specification.

This invention consists in improvements in airships of the Torrès type, and these improvements have for their object to dispense with all metallic parts and pieces hitherto employed in this type of airship for assembling the various constituent parts of the airship envelop.

15 The manner in which this invention is to be performed will now be more particularly described with reference to the accompanying drawings in which:

Figures 1 and 2 are respectively a longitudinal side elevation and a vertical cross-section of an airship of the Torrès type.

Figs. 3 and 4 are respectively a partial longitudinal elevation, and a vertical cross-section on the line 4—4 of Fig. 3, showing 25 the various parts that constitute the lower edge of an airship envelop constructed according to this invention.

Figs. 5 and 6 are respectively a plan and a vertical cross-section on the line 6—6 of 30 Fig. 5, of an improved device through which one of the groups of the suspension ropes passes.

The improved airship viewed from the outside comprises three reentrant angles, 1, 2, 3, formed by the longitudinal edges of 35 three lobes 4, 5, 6, circumscribing a triangle whose three angles constitute the apices of the reentrant angles 1, 2, 3, and whose three sides are formed by the girders 7, 8, 9, that 40 constitute the sides of the said triangle.

At each of the upper angles 1, 2, the following parts come together at the same point:

The fabric 10 of the upper lobe 5;

45 The fabric 11 or 12 of the corresponding side lobe 4 or 6;

The fabric of the corresponding girder 7 or 9;

The fabric of the top girder 8;

50 And the boltrope 13 or 14 to which are fixed the ropes 15 that constitute the internal suspension connected to the car 16.

These four fabrics are sewn together and 55 constitute each of the upper edges that form the lateral limit of the upper lobe 5.

For the purpose of facilitating the manufacture, the lower angle 3 is constructed in a different manner. The several fabrics 7, 9, 11 and 12, which come together at this angle, end separately in boltropes which are 60 laced together around two cords 17, 18, that constitute the lower edge of the airship. A tight joint is assured by means of a strap 19 sewn afterward on the outside of the fabrics, 11, 12.

65 The internal suspension ropes of the car starting from the boltropes 13, 14, are connected together in groups, and pass through the lower edge of the airship envelop and are connected to the car 16.

Hitherto, the attachment of the fabrics 7, 9, 11 and 12 around the cords 17 and 18 has been effected by a lacing comprising a cord passing through a suitable number of metal eyelets fixed to the boltropes of these 75 fabrics. Further, the internal suspension ropes 15 passed through the lower edge by being threaded through suitable metal parts.

Owing to this method of assembling, the 80 lacing eyelets and the metal parts through which the suspension ropes passed, were in contact with the gas in the envelop and were rapidly oxidized, and they corroded the lacing cords of the edge of the envelop.

The present invention has now for its object to remedy these various drawbacks, and it consists substantially in a system of lacing the several fabrics connected to the lower edge of an airship with internal suspension, 85 wherein no metal part capable of being oxidized is in contact with the gas in the envelop.

One of the essential characteristic features of the invention consists in that the four fabrics 7, 9, 11 and 12 connected to the 95 lower edge of the airship envelop, are sewn to boltropes 20, all similar to one another (Figs. 3 and 4). Inside each boltrope 20 there are inserted a number of wooden rods 21 arranged in line with one another. Each 100 rod 21 is provided with two collars 22, 23, passing through an aperture formed in the corresponding boltrope.

To form the edge of the envelop, the boltropes of the four fabrics are arranged in 105 such a manner that the collars 22, 23 of the rods will be opposite each other. Then the four corresponding rods 21 are arranged around the cords 17, 18 and fastened together as shown in Fig. 4, by means of a 110

strap 24, 25, consisting of a small cord ending in a loop at each end. The loop 24 at one end of the strap is engaged in the loop 25 formed at the other end after having tied 5 the four rods together.

A cord 26 passing successively through the loops 24 of the adjacent straps, prevents the fastenings thus formed from coming undone.

10 Another characteristic feature of the invention consists in that the apertures formed in the lower edge of the airship envelop for the passage of the suspension ropes 15 of the car 16, are formed by thimbles 27 of suitable 15 shape made of wood or any other inoxidizable material.

Each thimble 27, illustrated separately in Figs. 5 and 6, is formed on each side with longitudinal grooves 28 to receive the cords

20 17, 18, of the lower edge of the envelop. These cords are first separated from each other to form an opening in which the thimble is gripped, and at the ends of which they are then brought together and tied. Two 25 servings of yarn 29 serve to prevent the cords 17, 18, from coming out of the thimble.

Each thimble 27 is formed with a series of holes 30 by means of which are attached the respective rods 21 of the four boltropes.

30 For this purpose, the rods of the right-hand side of the envelop 11 and of the girder 7 are attached to the corresponding side of the thimble 27 by means of a strap 31 which passes through the holes 30 in the thimble 27 and is looped, as above described, around a fastening cord 32.

The arrangement is the same on the left hand side.

40 The arrangements hereinabove described are given solely by way of example, and it is to be understood that the shapes, dimensions and constructional details and applications may be varied without departing from the nature of the invention.

45 Having now described my invention, what I claim as new and desire to secure by Letters Patent is:—

1. In an airship of the Torrès type, non-oxidizable means for securing together the 50 edges of the fabrics constituting the lower edge of the envelop and allowing passage of internal suspension ropes, comprising in combination a series of rods respectively attached to the edge of each fabric, means for binding the rods together and to a continuous fastening rope, and means located between edges of the fabrics to receive and guide the internal suspension ropes of the airship.

60 2. An attachment device for securing together the edges of the fabrics constituting the lower edge of the envelop of an airship, comprising in combination a boltrope secured to the edge of each fabric, a rod extending through each boltrope, a strap ar-

ranged around the rods within the boltrope, a longitudinal fastening rope also embraced by the said strap, and means located between the edges of the fabrics to receive and guide the car suspension rope.

70 3. An attachment device for securing together the edges of the fabrics constituting the lower edge of the envelop of an airship, comprising in combination a boltrope secured to the edge of each fabric, a number 75 of rods embraced by each boltrope, the said rods being arranged in groups, a strap arranged around each group of rods, a longitudinal fastening rope also embraced by each of the said straps, whereby the latter 80 are retained in their position around the said arms, and means located between the edges of the fabrics to receive and guide the car suspension rope.

4. In an airship of the Torrès type, non-oxidizable means for securing together the edges of the fabrics, constituting the lower edge of the envelop and allowing passage of internal suspension ropes, comprising in combination a series of rods respectively attached to the edge of each fabric, means for binding the rods together and to a continuous fastening rope, a pair of ropes positioned within the aforesaid binding means, non-oxidizable thimbles carried by said pair 95 of ropes, a car, and internal suspension ropes secured to the car and passing through the thimbles.

5. In an airship of the Torrès type, non-oxidizable means for securing together the 100 edges of the fabrics constituting the lower edge of the envelop and allowing passage of internal suspension ropes, comprising in combination a series of rods respectively attached to the edge of each fabric, means for binding the rods together and to a continuous fastening rope, a pair of ropes positioned within the aforesaid binding means, non-oxidizable perforated thimbles, means whereby the thimbles are carried by said pair 105 of ropes, a binding means for securing together the said ropes and the said series of rods, a car, and internal suspension ropes secured to the car and passing through the thimbles.

110 6. In an airship of the Torrès type, non-oxidizable means for securing together the edges of the fabrics constituting the lower edge of the envelop and allowing passage of internal suspension ropes, comprising in 115 combination a series of rods respectively attached to the edge of each fabric, means for binding the rods together and to a continuous fastening rope, a pair of ropes positioned within the aforesaid binding means, non-oxidizable perforated grooved thimbles engaging said pair of ropes by the said grooving, binding means extending through the thimbles and engaging the said series of rods at each side, further means for securing the 120 130

ropes and thimbles together by encircling both the ropes and thimbles, a car, and internal suspension ropes secured to the car and passing through the thimble.

5 7. In an airship, the combination with a plurality of fabrics having looped meeting edges provided with spaced openings, of in-oxidizable rods located in the looped edges and having collars which project through 10 said apertures, and cords passed around said rods for securing the fabrics together.

8. A combination as defined in claim 7, in which each of the cords is provided with looped ends, one end of a cord after passing 15 around the rods being inserted through the loop at its other end, and means passed through the loop of the first end for securing said cord in place.

9. In an airship, the combination with envelop fabrics provided at their adjacent 20 edges with boltropes, of a member located at the adjacent edges of said fabrics and provided with grooved edges, ropes extending substantially parallel to the edges of said fabrics and resting in said grooves, said 25 member being provided with a series of spaced apertures, inoxidizable rods located in the boltropes at the edges of the fabric, means connected to said rods and passing through said apertures for securing the fabrics to said member and internal suspension 30 ropes secured to the envelop and passing through said member.

In testimony whereof I have signed my name to this specification.

HENRI KAPFERER.
